UNITED STATES PATENT OFFICE.

FRANCIS C. BAUER, OF CHATTANOOGA, TENNESSEE.

DESIGN FOR A KIMONO.

60,601.

Specification for Design.

Patented Mar. 14, 1922.

Application filed October 21, 1920. Serial No. 418,626. Term of patent 3½ years.

To all whom it may concern:

Be it known that I, FRANCIS C. BAUER, a citizen of the United States, and a resident of Chattanooga, in the county of Hamilton and State of Tennessee, have invented a certain new, original, and ornamental Design for Kimonos, of which the following is a specification.

I claim:

The ornamental design for a kimono as shown.

FRANCIS C. BAUER.
